UNITED STATES PATENT OFFICE.

ISAAC T. KAHN, OF CLEVELAND, OHIO, ASSIGNOR TO THE REPUBLIC STRUCTURAL IRON WORKS COMPANY, OF CLEVELAND, OHIO, A CORPORATION OF OHIO.

CONCRETE-INSERT.

1,280,485.

Specification of Letters Patent.

Patented Oct. 1, 1918.

Application filed December 12, 1914. Serial No. 878,822.

To all whom it may concern:

Be it known that I, ISAAC T. KAHN, a citizen of the United States of America, residing at Cleveland, in the county of Cuyahoga and State of Ohio, have invented certain new and useful Improvements in Concrete-Inserts, of which the following is a specification.

My invention relates to improvements in concrete insert, the object thereof being the production of a very simple and inexpensive member adapted for embedding in concrete structures for the purpose of supporting objects therefrom.

With the development of concrete buildings, it has become necessary to employ large numbers of inserts, and the desirability of producing the same very cheaply and of uniform type, has reached the point of acute demand throughout the trade. Numerous prior devices have been suggested and tried, but none with which I am acquainted, involving the use of castings or composite castings and sheet-metal devices depending upon the reinforcement of the concrete for support, may be as cheaply manufactured as the article herein set forth, embodying my invention.

Moreover, it is desirable, if not necessary, that these inserts shall be uniform in size and detail, in order that they may interchangeably be used for supporting weight from the ceilings of concrete buildings, and the like. After considerable experiment, I have found with the more obvious or ordinary method of forming inserts from sheet-metal, which is the most economical method known to me, the finished product is not uniform, due particularly to the deformation resulting from stamping out the slot in the lower face of the insert. Again, I have found that it is important to distribute the weight over areas of concrete not immediately engaged by the body of the insert and preferably of greater depth in the slab, than is common in the ordinary device upon the market.

Accordingly, I have devised a type of concrete insert which may be economically stamped from a single piece of sheet metal, suitably bent and slotted to form an open retaining compartment for the head of the supporting bolt or other member inserted therein. The several steps in the manufacture and slotting of this simple device,

together with the structural features thereof, will be fully explained in connection with the accompanying drawings, wherein:

Figure 1 is an inverted perspective view of the completed insert.

Fig. 2, is a side view thereof, partially broken away and in section, showing the device as positioned for embedding in the concrete.

Fig. 3, is a transverse sectional view on line 3—3.

Fig. 4, is a plan view of the blank, drawn upon a smaller scale, and Fig. 5 is another transverse sectional view of the device, partially shaped and ready for forming the slot 70 therein.

Throughout the several figures of the drawings, I have employed the same character of reference to indicate similar parts.

First I may describe the completed insert, best shown in Figs. 1 and 2, and then I will describe in some detail, the preferred method of manufacturing the same from an integral blank of sheet metal. The insert is provided with laterally extending ears *a* which are in a plane considerably above the body, of the structure, and accordingly are adapted to lie in the slab or concrete, and receive support from a very considerable thickness or body thereof. These ears are integral with downwardly bent straps *b* at right angles therewith (Fig. 2), between which the slotted face *c* of the insert is supported in turn. The usual keyhole slot *d* is formed in said face or bottom, while side pieces *e* and the top *g*, all bent from the same piece of sheet-metal, serve to complete the box-like structure of the insert for receiving the bolt head or nut *h* of the supported part.

Nail holes *a'* preferably are punched out of the ears *a*, for the purpose of fastening the insert in position upon the bottom *i* of the form. These ears *a* may be extended laterally for additional support, to any desired distance beyond the insert, while the connecting straps *b* may also be lengthened or shortened to position said ears at different levels for support within the concrete slab (not shown fully in the drawing.) (See dotted lines Fig. 2.)

It will be seen that the device of my improvement depends wholly upon the latterly extending supporting ears for carrying the supported weight within the concrete body.

as opposed to attaching the insert to any of the reinforcement with the concrete. Also the anchorage may be had at any desired depth within the concrete itself, hence my 5 improved insert may be positioned wherever desirable or necessary within the concrete structure.

Moreover, the keyhole slot may be varied in shape or size, to accommodate different 10 types of supported members, but these variable details do not pertain to my improvement and constitute mere modifications of the structure herein shown and described.

In Fig. 4, I have shown the blank from 15 which the insert may most readily be shaped. This is struck from sheet metal of any desired gage and the dotted lines indicate the keyhole punching and the bends respectively made in said blank. Ordinary practice would include the punching of the keyhole slot, but this I have found to be very undesirable with sheet metal, even of moderately heavy gage, for the reason that the subsequent bending of the blank deforms 20 the portions adjacent to the slot, and the resulting product is not uniform.

In order to produce a uniform insert from the blank herein shown, the ears and connecting straps are respectively bent at right 30 angles with each other and the latter at right angles with the bottom or lower face *c* of the insert. The top *g* also is bent at right angles with the side piece *f*, while said side pieces are bent at right and obtuse angles with the 35 bottom or lower face *c* of the structure, as best shown in the transverse sectional view, Fig. 5. The keyhole slot *d* is then punched in the lower face or bottom of the insert, after which the side pieces are bent to form 40 right angles with the bottom, as shown in Fig. 3, thereby bringing the top *g* into position for closing the box-like structure of the insert.

It will be understood that in explaining 45 the several steps of my improved method

for manufacturing this insert, I do not desire to be understood as specifying that the parts shall be bent at exact right angles, nor shall they form sharp angles, the one with the other, since this is not practicable with 50 metal of relatively heavy gage, and I have shown the angles generally curved or rounded in the different figures of the drawings.

Having now described the preferred insert of my invention, and the preferred method 55 for manufacturing the same, I claim as new and desire to secure by Letters Patent the following:—

1. A concrete insert shaped from a single integral sheet-metal blank punched to form 60 wide intermediate and narrow terminal members; said intermediate member being bent to form a chambered member closed at its top and sides having its lower face slotted for receiving, inclosing and affording clearance for the bolt-head, supporting end members positioned to close said chambered member and extending above the same, and terminals bent angularly from said end members to afford support in an upper 65 stratum of the concrete, substantially as set forth.

2. A concrete insert comprising an integral sheet metal blank punched to form 70 terminal end portions and a wide intermediate body portion; said body portion having an opening or slot punched therein, side portions bent upwardly and then horizontally to form a top for the resulting box-like body, and said end portions being bent vertically 75 as uprights to close the ends of said body portion and afford supporting members extending above the same, substantially as set forth.

In testimony whereof I affix my signature in the presence of two witnesses.

ISAAC T. KAHN. [L. S.]
